UNITED STATES PATENT OFFICE.

WILLIAM EVANS WOODS AND LESTER ARTHUR BENSON, OF ST. LOUIS, MISSOURI.

DESIGN FOR A CASING FOR A ROTARY SPARK-GAP.

58,859.

Specification for Design.

Patented Aug. 30, 1921.

Application filed January 18, 1921. Serial No. 438,254. Term of patent 7 years.

To all whom it may concern:

Be it known that we, WILLIAM EVANS Woods and LESTER ARTHUR BENSON, citizens of the United States, residing in the city and county of St. Louis, State of Missouri, have invented a new, original, and ornamental Design for a Casing for a Rotary Spark-Gap, of which the following is a specification, reference being had to the accompanying drawing, forming a part thereof.

The figure is a perspective elevational view of a casing for a rotary spark gap showing our new design.

We claim:

The ornamental design for a casing for a rotary spark gap as shown.

WILLIAM EVANS WOODS.
LESTER ARTHUR BENSON.
